COMMUNICATION SPEAKER FOR MASKS

Maxwell Berman, Los Angeles, Calif., assignor to
Douglas Aircraft Company, Inc., Santa Monica, Calif.

Filed Sept. 12, 1962, Ser. No. 71,662

Term of patent 14 years

(Cl. D26—14)

FIGURE 1 is a front elevational view of a communication speaker for masks embodying my new design;

FIGURE 2 is a side elevational view;

FIGURE 3 is a bottom plan view; and

FIGURE 4 is a rear elevational view thereof.

The dominant features of my design reside in the portions shown in full lines, and the broken line showing of a representative mask is for illustrative purposes only.

I claim:

The ornamental design for a communication speaker for masks, substantially as shown and described.
